[57] CLAIM

The ornamental design for a notepad attachment for a telephone, substantially as shown and described.

DESCRIPTION

FIG. 1 is a perspective view of a notepad attachment for a telephone showing my new design;

FIG. 2 is a top plan view thereof;

FIG. 3 is a bottom plan view thereof;

FIG. 4 is a front elevational view thereof;

FIG. 5 is a rear elevational view thereof; and

FIG. 6 is a right side elevational view, the left side being a mirror image thereof.

*FIG. 1**FIG. 2**FIG. 5**FIG. 3**FIG. 4**FIG. 6*
